UNITED STATES PATENT OFFICE.

MALCOLM BENTZON, OF LONDON, ENGLAND.

APPARATUS FOR THE MANUFACTURE OF LENSES.

1,072,419.

Specification of Letters Patent.

Patented Sept. 9, 1913.

Application filed July 23, 1911. Serial No. 641,069.

To all whom it may concern:

Be it known that I, MALCOLM BENTZON, a subject of the King of Great Britain, residing at 188 Strand, London, England, have 5 invented new and useful Improvements in Apparatus for the Manufacture of Lenses, of which the following is a specification.

My invention relates to apparatus for grinding and polishing bi-focal and other 10 lenses and to that class of apparatus forming the subject of pending application Serial No. 528,800 of which I am one of the inventors and wherein the grinding tools are capable of oscillatory motion on the driving spindles.

15 The specification of the said pending application describes *inter alia* an apparatus wherein a series of grinding and polishing tools is arranged to operate simultaneously on the outer curvature of the lens, the tools 20 in one arrangement being carried by separate heads and in another arrangement carried on a common driving shaft. In this latter arrangement, however, the said tools not only rotate on their own axes but also 25 revolve around the axis of the lens and this dual movement of the grinding tools presents difficulties in connection with the construction and operation which very much detract from the practical utility of the apparatus, furthermore with this latter arrangement all the tools rotate in the same direction, whereas, in practice, it is advisable 30 that some of the tools should rotate in one direction and some in the other.

35 Now, according to my present invention, I mount the spindles for the several grinding tools in a fixed head so that the said tools have only a motion of rotation on their axes, the rotation of the lens holder beneath the 40 grinding tools serving to bring all the parts of the lens under the action of the tools.

In a suitable arrangement for carrying out my invention, the spindles are mounted in bearings in a fixed head, springs being arranged in connection with the spindles for enabling them to yield to a certain extent in a longitudinal direction for the purpose of causing the tools to act upon the surface being ground with spring pressure. The 45 said bearings may be adapted to be adjusted at an angle so as to enable them to be fixed in position normal to the surface being ground.

The spindles may be driven in any suit-

able manner, but I find it advantageous to 55 drive them independently, through the medium of flexible shafts from the several wheels of a chain of gear wheels, to one of which rotary driving motion is imparted, this arrangement of flexible shafts and gearing 60 allowing of the necessary longitudinal movement of the spindles under the action of the springs, and also providing for rotating some of them in one direction and some in the other direction.

65 Where it is desired to provide for varying the distance between the centers of the grinding tools according to the diameter of the grinding tools used, or of the lens being ground, I can arrange the spindles in slots 70 in the head, and provide a series of templets having notches or slots corresponding with the varying positions in which it may be desired to place the spindles and which templets can be applied to the head to embrace 75 the spindles, and to retain them in their proper axial positions.

The arm which supports the head upon the base may advantageously have a sliding adjustable saddle upon it carrying the table 80 upon which the lenses are fixed for grinding, and which table, as hereinbefore stated, is adapted to be rotated beneath the grinding tools.

To enable my invention to be fully understood, I will describe the same by reference to the accompanying drawing, in which:

Figure 1 is a sectional side elevation of my improved apparatus. Fig. 2 is a plan with the cover removed. Fig. 3 is a section 90 on the line 3--3. Fig. 1. Fig. 3^a is a detail elevation of the tool operating spindles and their carrying arms. Fig. 4 is a section on the line 4--4 Fig. 1 looking in the direction of the arrow in the said figure, and Fig. 5 is 95 also a section on the line 4--4 but looking in the reverse direction to that of the arrow.

Fig. 1 indicates the pillar or standard of the machine, which, as shown, is of triangular shape in cross section and fixed at its lower 100 end to a base *b*, while at its upper end it carries a plate *c* to which the head *d* carrying the grinding spindles is fixed.

As shown, this head *d* comprises top and bottom plates *e*, *e*¹ with an intermediate ring 105 or shell *f* which is clamped between the plates *e*, *e*¹ and held in position by means of screws *g*, *g* which pass through the plate *c*,

and serve also for drawing the head up against the underside of the said plate to secure it in place.

5 h, h are arms (one of which is shown detached in Fig. 3^a) pivoted at h^1 to the plates e, e^1 as indicated in Figs. 3 and 4, and carrying at their free ends bearings in which the spindles i, i for operating the grinding tools are mounted. Each of the spindles as 10 shown, has upon it a collar j , between which and the upper side of an opening k in the arm h is located a spring j^1 which allows of the longitudinal movement of the spindle in the bearing. The upper ends of the spindles i , which project above the plate e , are adapted to have connected to them means for driving them; as shown in the drawing each spindle has connected to it one end of a flexible shaft l , the other end of which is 15 secured to the boss of a gear-wheel m .

20 The several gear-wheels m, m , which are all of the same diameter, are geared together and receive their motion through a spindle n attached to one of them so that they will 25 all rotate simultaneously (some in one direction and some in the other) at the same speed and transmit their movement to the several spindles i, i . The lower ends of the spindles i, i are provided with carriers i^1, i^2 , 30 or adapted in any other suitable manner for connection with grinding tools of the kind described in the specification before referred to.

35 The plates e, e^1 have formed in them curved slots e^2, e^2 through which the spindles i, i pass so as to allow of the spindles i, i being arranged radially nearer to or farther from the center of the head, as desired, and the position of the said spindles is 40 regulated by the employment of a templet o having formed upon it a series of hooks designed to engage with the spindles in a manner which will be readily understood by reference to Figs. 3 and 4. This templet is applied to a central pin p passing through the head, the hook portions being passed between the carriers, and the templet then turned to engage the hooks with the spindles.

45 50 To allow for locking the templet in position the central pin p is mounted on an eccentric q carried by a spindle q^1 the rotation of which serves to move the said pin longitudinally, the central hole in the templet being made large enough to pass over an adjustable nut p^1 on the lower end of the said spindle q . To hold the templet on the pin p above the nut p^1 , I provide a loose slotted collar r , which, when the said pin is 55 60 in its lowest position, is introduced between the said nut and the templet in such a manner that when the spindle q is turned to lift the pin p , the templet is drawn tightly against the under plate e^1 of the head.

65 It is to be understood that when a machine

is intended to be used for grinding lenses of different diameters, templets of varying size may be employed for holding the spindles either farther away from, or nearer to, the center of the head than shown.

70 Although I have described the use of a templet o for adjusting the position of the spindles i, i it is to be understood that any other means suitable for the purpose may be employed.

75 s is the saddle adjustable upon the standard a and carrying the spindle t to which the grinding table is fixed in a well known manner. As shown, this saddle has a shield u upon it for protecting the standard from 80 the abrasive powder used in the grinding operation, the lower part of the said shield being composed of sections which telescope one into the other.

Claims.

1. In a lens grinding and polishing machine, the combination with a vertical pillar or standard and a fixed horizontally disposed head secured to the upper end of the said standard, of a work support adjustably mounted on the said pillar or standard, a rotatable table mounted on the said support, a plurality of rotatable grinding tool operating spindles mounted in said head and means for simultaneously rotating said spindles.

2. In a lens grinding and polishing machine, the combination with a fixed horizontally disposed head, of a rotatable work support located below the same, a plurality of 100 rotatable grinding tool operating spindles mounted in said head, driving means for rotating said spindles simultaneously, connections between said driving means and certain of said spindles for rotating them in one direction and connections between said driving means and others of said spindles for rotating them in the opposite direction.

3. In a lens grinding and polishing machine, the combination with a fixed horizontally disposed head, of a rotatable work support located below said head, a plurality of vertically disposed rotatable tool operating spindles mounted in said head, means for adjusting each of said spindles substantially 110 radially with respect to the work support and means for driving said spindles.

4. In a lens grinding and polishing machine the combination with a fixed horizontally disposed head of a plurality of pivoted arms adapted to swing laterally in said head, a tool operating spindle carried by each of said swinging arms, means for positively operating the several spindles independently, a rotating work supporting table and 120 means for securing the said arms and spindles uniformly around the axis of the said work support.

5. In a lens grinding and polishing machine, the combination with a fixed hori- 130

zontally disposed head, of a rotatable work support located below said head, a laterally swinging arm pivotally mounted in said head, a tool operating spindle carried by said swinging arm, said head being provided with a curved slot concentric with the pivotal connection of said arm, to permit the passage of the spindle therethrough, and securing means engaging said arm for holding it in fixed relation with the work support.

6. In a lens grinding and polishing machine, the combination with a horizontally disposed head, of a rotatable work support located below the said head, a laterally swinging arm pivotally mounted in said head and provided adjacent to its outer end with bearing portions, a vertically disposed rotatable spindle carried in said bearing portions, said head being provided with a curved slot for the passage of the spindle and the adjacent bearing portion therethrough, and a securing device engaging said bearing portion of the arm for holding said arm and spindle in fixed relation with the work support.

7. In a lens grinding and polishing machine, the combination with a horizontally disposed head, of a rotatable work support located below said head, a laterally swinging arm pivotally mounted in said head, a spindle mounted in said arm adjacent to the outer end thereof, means for securing said spindle in fixed relation with said work support, said spindle and work support the one with yielding means for pressing it toward the other.

8. In a lens grinding and polishing machine, the combination with a horizontally disposed head, of a rotatable work support located below the said head, of a laterally swinging arm pivotally mounted in said head, a rotatable tool operating spindle mounted in said arm adjacent to the outer end thereof, a spring interposed between the spindle and a part connected with said arm for pressing the spindle longitudinally toward the work support and devices for holding said arm and spindle in fixed relation with the work support.

9. In a lens grinding and polishing machine, the combination with a horizontally disposed fixed head, of a rotatable work support located below said head, a laterally swinging arm pivotally mounted in said head and provided with bearing portions adjacent to its outer end, a tool operating spindle mounted in said bearing portions and provided with a collar, a coiled spring encircling said spindle and interposed between said collar and a portion of said arm, and devices for holding said arm in fixed relation with said work support.

10. In a lens grinding and polishing machine, the combination with a fixed horizon-

70 tally disposed head, of a rotatable work support located below the same, a plurality of laterally movable tool operating spindles movably mounted in said head and a detachable templet for holding said spindles in fixed relation with the work support.

11. In a lens grinding and polishing machine, the combination with a fixed horizontally disposed head, of a rotatable work support located below the same, a plurality 75 of swinging arms mounted in said head, tool operating spindles, mounted one in each of said arms and movable in a substantially radial direction with respect to the axis of the work support and a templet having portions for engaging parts connected with said spindles for holding them in fixed relation with the work support and means for detachably securing the said templet to the head.

80 12. In a lens grinding and polishing machine, the combination with a fixed horizontally disposed head, of a rotatable work support located below the same, a plurality 85 of swinging arms mounted in said head, tool operating spindles, mounted one in each of said arms and movable in a substantially radial direction with respect to the axis of the work support and a templet having portions for engaging parts connected with said 90 spindles for holding them in fixed relation with the work support, a vertically movable securing bolt for said templet mounted in said head and provided with a collar for engaging the templet, and devices for operating said bolt.

95 13. In a lens grinding and polishing machine, the combination with a fixed horizontally disposed head, of a rotatable work support located below the same, a plurality 100 of swinging arms mounted in said head, tool operating spindles, mounted one in each of said arms and movable in a substantially radial direction with respect to the axis of the work support and a templet having portions for engaging parts connected with said 105 spindles for holding them in fixed relation with the work support, a vertically movable locking bolt for said templet, a clamping collar on said bolt for engaging 110 the templet and an adjustable part on said bolt for engaging said collar.

115 14. In a lens grinding and polishing machine, the combination with a fixed horizontally disposed head, of a rotatable work support located below the same, a plurality of 120 swinging arms mounted in said head, tool operating spindles, mounted one in each of said arms and movable in a substantially radial direction with respect to the axis of 125 the work support and a templet having portions for engaging parts connected with said spindles for holding them in fixed relation with the work support, a vertically movable securing bolt mounted in said head and pro- 130

vided with an enlarged part at its lower end, said templet having an aperture to accommodate said enlarged part, a detachable collar adapted to be inserted between the 5 said enlarged part and the templet and means for moving said bolt longitudinally.

15. In a lens grinding and polishing machine, the combination with a fixed horizontally disposed head, of a rotatable work 10 support located below said head, a laterally swinging arm pivotally mounted in said head, a tool operating spindle carried by said swinging arm, and means for securing said arm and spindle in fixed position with 15 respect to the work support, a rotary driving part for said spindle and a flexible shaft connecting said driving part with said spindle.

16. In a lens grinding and polishing 20 machine, the combination with a fixed head, of a rotatable work support located below the same, a plurality of laterally movable tool operating spindles mounted in said head, means for securing said spindles in 25 fixed relation with the work support, a driving shaft provided with a pinion, a plurality of pinions engaging the driving pinion, and flexible shafts extending one from each of said spindles to one of said pinions.

30 17. In a lens grinding and polishing machine, the combination with a fixed head and a work support located below the same, of a plurality of laterally movable tool operating spindles mounted in said head, 35 means for securing said spindles in fixed relation with the work support, said spindles being movable longitudinally with respect to the head, a depressing spring connected with each spindle, driving mechanism and 40 flexible connections from said spindles to the driving mechanism.

18. In a lens grinding and polishing machine, the combination with the work support provided with a rotary work holder, 45 of a fixed head located above the work support, a plurality of laterally swinging arms mounted in said head, a tool operating spindle carried by each of said arms, means for securing said arms and spindles in fixed 50 relation with the work support, said spindles

being longitudinally movable in said arms, depressing springs carried one by each of said arms and engaging the spindle carried thereby, driving mechanism for operating said spindles simultaneously and a flexible 55 shaft from each of said spindles to the said driving mechanism.

19. In a lens grinding and polishing machine, the combination with a vertically disposed pillar, a fixed head supported 60 thereby at one side of the pillar, and comprising parallel horizontal plates, horizontally swinging arms pivotally mounted between said plates, a spindle mounted in bearings adjacent to the outer end of each 65 arm, and provided with a collar, a spring surrounding each of said spindles and interposed between the said collar and a portion of the arm, the lower of said horizontal plates of the head being provided with 70 curved slots for the passage of said spindles, and the adjacent portions of their bearings, a removable templet provided with hook shaped portions engaging the spindle bearings, to hold the spindles in a predetermined relative position with respect to the work, a vertically movable locking bolt for securing the templet in position passing vertically through the horizontal plates of 75 the head and provided at its lower end with 80 an adjustable device, a locking spindle provided with an eccentric portion engaging said bolt, the templet being provided with an aperture for the passage of the bolt, a removable slotted collar for engaging the 85 said bolt above the adjustable device thereon, a work support secured to the pillar and adjustable vertically thereon, and a rotary work holding spindle carried by said work support, a vertical driving shaft carried by 90 said pillar, and driving pinion secured thereto, a plurality of pinions in engagement with said driving pinion and curved flexible shafts connecting each of the tool spindles with one of said pinions.

MALCOLM BENTZON.
